UNITED STATES PATENT OFFICE.

LOUIS SCHLECHTE, OF ST. LOUIS, MISSOURI.

SHUTTER-FASTENER.

SPECIFICATION forming part of Letters Patent No. 273,164, dated February 27, 1883.

Application filed December 4, 1882. (No model.)

To all whom it may concern:

Be it known that I, LOUIS SCHLECHTE, of the city of St. Louis, in the State of Missouri, have invented a certain new and useful Improvement in Shutter-Fastenings, of which the following is a full, clear, and exact description, reference being had to the accompanying drawings, forming part of this specification, and in which—

10 Figure 1 is an outside view of two shutters with my fastening applied. Fig. 2 is an inside view of same. Fig. 3 is a transverse section taken on line 3 3, Fig. 2. Fig. 4 is a detail vertical section taken on line 4 4, Fig. 2, with the latch in its lower position; and Fig. 5 is a similar view with the latch raised, unfastening the shutters.

20 My invention relates to a shutter-fastening that can be operated to unfasten the shutters from the outside by means of a stream of water, in case of fire, from the hose of a fire department; and my invention consists in the special construction of the device, as herein-after fully described.

25 Referring to the drawings, A A' represent the shutters, and B their hinges.

C is a latch pivoted by one end to the inside of the shutter A. Its free end is sustained by a keeper, D, secured to the inside of 30 the shutter A. The keeper is sufficiently long to allow the latch to be raised, as shown in Fig. 5 and by dotted lines, Fig. 2.

35 E represents a catch secured to the inside of the shutter A', near the edge thereof, which receives the free end of the latch C, thus holding the shutters in their closed position. When the latch is raised, as before mentioned, it is disengaged from the catch, allowing the shutters to swing open.

40 Secured to the latch C is a flat thin plate, F, by means of a neck, G, extending through a semicircular slot, H, in the shutter A, the plate thus being on the outside of the shutters, with a flat side down, as shown, where it can

be operated upon to raise the latch, unfastening the shutters, by a stream of water, in case of fire, from the hose of a fire department. When the latch is thus raised the shutters will spring slightly open, giving an opportunity for a stream of water to be directed between them, which will force them open.

I represents a pin secured to the free end of the latch and projecting inward, by which the latch can be raised from the inside of the shutters.

55 I am aware that it is not new broadly to raise the latch of a shutter-fastening from the outside by means of a stream of water from the hose of a fire department, therefore I do claim to be the inventor thereof; but

60 What I do claim as my invention, and desire to secure by Letters Patent, is—

1. In a shutter-fastening, the combination of latch C, pivoted by one end to the shutter A, keeper D, secured to the shutter A, to sustain the free end of the latch, catch E, secured to the shutter A', and engaging with the free end of the latch, flat plate F, with neck G, secured to the latch C, and semicircular slot H in the shutter A, through which the stem of 70 the plate F passes, all substantially as and for the purpose set forth.

2. In a shutter-fastening, the combination of latch C, pivoted by one end to the shutter A, keeper D, secured to the shutter A, to sustain the free end of the latch, catch E, secured to the shutter A', and engaging with the free end of the latch, plate F, on the outside of the shutter, and having a neck, G, secured to the catch C, semicircular slot H in the shutter A, 80 through which the stem G passes, and inward-projecting pin I on the free end of the catch C, all substantially as and for the purpose set forth.

LOUIS SCHLECHTE.
